VACUUM CLEANER

Ward Leathers, Haworth, N. J., assignor to
Quadrex Corporation, New York, N. Y.

Application August 3, 1938, Serial No. 222,817

2 Claims. (Cl. 15—13)

My invention pertains to the nozzle or carpet contacting portion of a vacuum-cleaner and has to do particularly with that type of nozzle wherein motive power is used for beating the carpet.

The object of my invention is to produce such power-driven beating device for use on any type of vacuum-cleaner wherein the power available is separate and distinct from that used by the motor of the motor-blower-unit. Where the same source of power is used for both purposes sacrifice of desirable characteristics must be made, i. e. where the beater is operated sufficiently slowly by a belt reduction to obtain a none too fast beating cycle, the blower fan joined to the motor shaft rotates too slowly to give efficient, centrifugally-generated air-suction/air volume.

A further object of my invention is to use an electro-magnetic power-application other than a rotary motor because where such an additional motor is used for operating the beating equipment in a vacuum-cleaner nozzle the bulk is too great and the nozzle too high to go under furniture. In that case it becomes almost another vacuum-cleaner in bulk and weight. Such arrangements have proved unsatisfactory. My arrangement and power-application keep the nozzle small in bulk and sufficiently low to pass under low furniture as is now possible with plain suction nozzles used on hose-type machines.

A further object of my invention is to obtain a very amply powered oscillating mechanism for beating purposes and to produce an electro-motively actuated, oscillating or beating mechanism with a minimum of electric complication, i. e., the complete elimination of current make-and-break mechanism in the nozzle itself. I have obtained this desired result by driving the make-and-break or timing mechanism off the motor used for driving the suction blower.

A further object of my invention is to produce a beating mechanism of the above type, in the type of nozzle which lifts the carpet from the floor, beats it, passes the incoming air over the point of beating, makes-and-breaks the incoming air for increasing its speed during pulsation, and to obtain such carpet lifting-and-beating function on all types of carpets, high or low pile, without any manual adjusting whatsoever. In other words, the nozzle is automatically adjusted to the carpet where heretofore nozzles for the lifting-and-beating purpose have required adjustments for different types of rug or carpet.

My power-driven, oscillating, beating nozzle is applicable to all types of portable vacuum-

cleaners. It is especially applicable to the canister or hose-type machines now in use whether built with horizontal or vertical axis; it is applicable to the types of machine that carry the motor-blower-unit rigid with the operating handle, and with slight modification the device as shown may be rigidly joined to the conventional bag-type cleaner.

Other objects will appear in the following detailed description of the invention, illustrated in the accompanying drawings, of which:

Figure 1 is a longitudinal, diagrammatic cross-section.

Figure 2 is a partially broken plan view of the under side of the nozzle.

Figures 3, 4, and 5 show side, top, and end views respectively of the regenerative springs.

Figure 6 shows an application to a vertical axis canister-type machine.

Figure 7 shows a diagrammatic, partially cross-sectioned view of a timer.

Figure 8 is a wire diagram.

A rigid, lateral, nozzle member 1, Figs. 1 and 2, preferably a die-casting, is covered by a flexible rubber shoe 2. Die-casting 1 is joined by means of a hollow trunnion joint 3 to any means of air intake 4 to the vacuum-cleaner (where the nozzle is used on a conventional bag-type cleaner this joint may be omitted). The type

30 of flexible trunnion joint as shown is fully set forth in my co-pending application Serial No. 218,645. A pair of electric conductors 5 supply current to conductors 6 within the nozzle through a flexible connection 7. Where this nozzle is 35 applied to a hose-type machine the current is provided by means described in my co-pending application Serial No. 216,011. A beater bar 8, preferably of hard fibre, runs substantially the length of the opening on the under side of the

40 nozzle and is joined to a supporting member 9 of substantially equal length made of magnet-iron. This member is joined in suitable manner to sections of clock-spring 10 which are in turn joined at their forward end, in a hingeable manner, to the nozzle casting 1. A rubber partition 12 joined to the top of the beater bar in

45 suitable manner is also joined to the case 1 for purposes of keeping the incoming dirt-laden air within a confined nozzle chamber 12. Disposed beneath the beater bar mechanism just recited is a metal bed-plate 13 which is hingeably joined to the case 1 at points adjacent the junctures of the clock-spring 10. Anchored securely to the bed-plate is a series of electro-magnets 15 supplied with coils 16. The beater bar 8, due to

the springs 10, is free to move up and down in an arcuate manner; the bed-plate with its magnets is free to move with respect to the nozzle in a similar manner. The beater bar mechanism is disposed immediately above the electro-magnets in such manner that when the magnets are electrically activated, beater bar 8 is drawn violently downward. Pads 17 on the rigid nozzle member 1 and 18 on the bed-plate 13 aid in holding the nozzle sufficiently free from the floor to permit suction-lifting of the carpet and the intake of most of the admitted air at the front edge of the nozzle which makes cleaning close to base-boards and the like practicable.

It is not the intention that the magnetic effect should be sufficient to do any suitable beating of the carpet were it not for the all-important regenerative springs, hereinafter described, used in conjunction therewith.

Disposed at intervals along the beater bar mechanism just described, are springs 20, Figs. 3, 4, and 5, which regenerate the downward acting energy applied to the beater bar by the magnets when the current is broken. Immediately above these springs is a substantially similar series of springs 21 for resisting the upward motion of the beater bar and regenerating the over-thrown. A suitable separator 22 is disposed between these springs, and bracket-like supports 23 hold the spring mechanism in fixed relationship to the bed-plate 13. Notches 25 cut in the magnet iron 9 permit a suitable telescoping of the beater bar unit and the spring mechanism and suitably dispose a portion of the member 9 between the tips of the springs 20 and 21. It should be noted that these springs are so designed as to comprise a two-way-stop-spring-mechanism, i. e. the springs that may be deflected in their desired direction only from a fixed position.

In Figure 6 I have shown my nozzle applied to a vertical axis canister hose-type vacuum-cleaner 30 in which the motor 31 (used for creating the vacuum and hence the air-flow in the machine) is geared to a timer 32 electrically connected by leads 33 through a hose 34 and an extension tube or wand 35 to the nozzle 36. The extension tube 35 is also provided with a lamp and lighting device 37.

Any type of suitable timer may be employed. A suitable form, shown diagrammatically in Fig. 7, comprises a rotating carbon brush 40 supported in a holder 41 firmly joined to worm-gear 42, suitably housed in a case 43, driven by a worm on the motor shaft 44, and electrically connected through leads 45 and 46. Make-and-break is accomplished by methods common to distributors used on internal combustion engines. The speed cycle of this timer is establishable by the ratio between worm-gear 42 and worm 44, and represents that ratio with the R. P. M. of the motor. For illustration, if the motor normally turns 12,000 R. P. M., a suitable speed for centrifugal air compressor common to vacuum-cleaners, and the gear ratio is 25 to 1, the electric impulses sent from this timer to the nozzle would be eight per

second. The duration of the impulse is determined by the length of arc of the contact member 50 in the housing 43.

A wire diagram, Fig. 8, shows the coils 16 in the nozzle wired in parallel from the timer 32. The motor 31 is controlled by the switch 62 on the machine and the lamp 63 is parallel with the coils.

In operation this nozzle beating mechanism functions by the laws of vibration. The electric impulses are so timed with respect to the characteristics of regenerative springs and oscillating member as to amplify the vibratory action in the most efficient manner. When the weight of the beater bar mechanism, the spring throw and resistance, the energy of magnetism, the timing and duration of energization are in proper relationship a very powerful oscillating motion is obtained on the beater bar. While the speed of oscillation can be changed at will by the gear ratio, this speed must bear a correct relationship to the natural oscillatory period of the moving parts in the nozzle. When the best proportions are obtained this electro-magnetic power device reaches relatively high electro-motive efficiency and the beating force obtainable with a modest current (such as, 200 to 300 watts half the time) is very ample for the purposes set forth.

Having disclosed my invention in this specification sufficient for clear understanding by those familiar with these arts, I wish to make note of the fact that the constructions and methods used are susceptible to wide variation in practice by the application of mechanical skill, without departing from the spirit and novel character of my invention.

What I claim is:

1. In a suction cleaning tool with a suction inlet having parallel lips forming the two longer sides of said inlet, a carpet-agitating-beating member disposed between said lips and comprising an armature, an electro-magnet member also disposed within said tool, said members pivotally joined to one of said lips inwardly of the cleaning tool and in such manner that their weights are carried substantially independently of each other and of the tool itself by the napped surface undergoing cleaning, and with means interposed between the said members for holding the armature normally free from the electro-magnet.

2. In a suction cleaning tool with a suction inlet having parallel lips forming the two longer sides of said inlet, a carpet-agitating-beating member disposed between said lips and comprising an armature, an electro-magnet member also disposed within said tool, said members pivotally joined to one of said lips inwardly of the cleaning tool and in such manner that their weights are carried substantially independently of each other by the napped surface undergoing cleaning, and a spring joined to one of said members and positioned to co-act with the second said member when the said magnet intermittently and magnetically pulls the two said members together.

WARD LEATHERS.
